UNITED STATES PATENT OFFICE.

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK.

TRAIN-CONTROL SHOE MECHANISM.

Application filed May 14, 1921. Serial No. 469,529.

To all whom it may concern:

Be it known that I, ARCHIBALD G. SHAVER, a citizen of the United States, residing at Chicago, in the county of Cook and State 5 of Illinois, have invented certain new and useful Improvements in Train-Control Shoe Mechanism, of which the following is a specification, reference being had therein to the accompanying drawing.

10 This invention relates to train control shoe mechanism adapted for use in conjunction with automatic train control systems to control switch members for both the train carried circuits and the roadside circuits.

15 In the improved construction there is carried in the upper portion of a suitable box or chamber a fixed piston, while in the lower portion is disposed a sliding cylinder, the extreme lower end of which is provided 20 with an adjustable ramp engaging shoe.

Carried by the cylinder is a contact member of novel construction which will permit of the rotation of the cylinder without disturbing the electrical contacts; this rotating 25 feature permitting the shoe, when engaging the ramp, to rotate about the axis of the cylinder, thus presenting different wearing surfaces and, at the same time, having a tendency to clear the ramp and shoe face of 30 any obstruction. The ramp contacting member is also adjustable and is mushroom shaped, so that in meeting any obstruction along the line it has a greater tendency to ride over the same without breaking the 35 cylinder.

In the accompanying drawings:

Figure 1 is a front elevation, partly in section, of the complete shoe.

Figure 2 is a section taken on line 2—2 40 Fig. 1, the cylinder and piston being shown in elevation.

Figure 3 is a horizontal section on line 3—3 of Figure 1.

Figures 4, 5, 6, and 7, are detailed views of 45 parts of the mechanism.

Referring to the drawings, the numeral 10 designates the casing having the surrounding walls 10', which constitutes a box for the main elements, the lid 10'' being 50 attached removably in place by bolts 10'''.

Mounted in the upper wall of the casing, with the piston portion 11 projected within the casing, is the stationary piston of the device, its base 11' being disposed above and 55 attached exteriorly to the casing. The pis-

ton 11 is hollow and open at the lower end and its base 11' contains passages and ports for direct connection with the brake system.

In the lower portion of the casing 10' there is disposed a cylindrical insulating 60 bushing 12, having adjacent to the ends thereof two washers 12' of the same material to insulate the metal bushing 13 from the casing, said bushing 13 being held in place by the integral rim 13' at one end and the 65 detachable rim 13'' at the other end.

Mounted for vertical sliding movement and also rotation within bushing 13, is the cylinder 14, the upper end of which surrounds the lower end of piston 11 and is 70 provided with the stuffing box 14a. The lower end of the cylinder is provided with screw threads 14', the purpose of which will presently appear, while intermediate of its ends it is provided with the shoulder 14'', 75 which limits its downward movement. At a short distance above the shoulder 14'' is a cylindrical enlargement 15 having two projecting flanges 15' which form a receptacle for a removable contact ring 16 which 80 is split and attached in place by means of screws.

The cylinder 14 is provided with graduated chambers or ducts 14b, 14c, and 14d, which provide a venting or air-admitting 85 chamber, should the cylinder break due to striking an obstruction.

Four arms 18 are carried by a plate or support 19, these arms each having upon their respective terminals a sleeve 18' for 90 sliding engagement with fixed guide rods 17, there being two of these. The support 19 is provided with spaced lugs 20, which are adapted to fit astride of the flanges 15'. Attached to the support 19 adjacent to this 95 point, and extended to resiliently engage the ring 16 are two contact arms 21, thus establishing electrical connection in a most desirable manner with the cylinder, without interfering with the rotation thereof. 100

To the outer face of the support 19 are attached by means of bolts 22, the insulating supporting plates 23, there being attached to the same the two oppositely disposed parallel switch members or blades 24.

Disposed to co-operate with the blades 24 are suitably disposed terminals 27, 28, 29 carried for example by the bars 26 which are supported in the brackets 25 within the casing. The terminals can be disposed in 110

any other desired manner according to the purpose for which they are used.

Adapted to adjustably fit upon the threaded portion 14' of the cylinder 14 is the 5 ramp engaging or contact member 30 which is here shown as an exaggerated mushroom and with a relatively deep internally threaded socket 31, there being provided the two oppositely disposed set screws 32, or if desired, a single transverse locking bolt passing 10 through elongated slots to permit of securing the contact member within certain limits of adjustment fixedly to the cylinder so as to be bodily moved therewith.

15 When the shoe is used with air pressure brake systems, the air under pressure entering the hollow piston and cavities in the cylinder tends to keep the latter protruded except when the shoe is temporarily raised 20 against such air pressure by passing over a ramp, but where vacuum is employed a spring or springs, weights or other means must be used to protrude the cylinder.

It will be seen that the ramp engaging 25 member 30 is in electrical connection, through the cylinder 14, flanged member and contact ring 16, contact member 21 and through a flexible connection not shown to any of the contacts desired, (preferably 29 left). The contact plates 24 in the position 30 illustrated bridge the contacts 27 and 28 respectively, but when the cylinder rises on a ramp further contact is first made with 29 and then the blades 24 leave the lower 35 contacts 27, thus making and breaking certain circuits whereby the brakes are operated when needed in a manner forming no part of the present invention. The arrangement of contacts 27, 28 and 29 is thus 40 illustrated only and the invention is not confined to any special number or arrangement of contacts.

What I claim as new is:

1. A ramp shoe for train control systems 45 including a support, a fixed piston carried by the support and normally in communication with an air brake system, a sliding cylinder mounted in the system and cooperating with the piston, said cylinder being 50 mounted for sliding and rotatable movement and having its lower end closed, a ramp engaging member carried by the lower end thereof, and cooperative circuit controlling means carried by the support and by the cylinder.

2. A ramp shoe for train control systems 60 including a support, a fixed piston carried by the support and normally in communication with an air brake system, a sliding cylinder mounted in the system and cooperating with the piston, said cylinder being 65 mounted for sliding and rotatable movement and having its lower end closed, a ramp engaging member carried by the lower end thereof, an annular contact member

carried by the cylinder within the support, a sliding switch member operably engaging the same, means for guiding the same in vertical movement, and fixed switch members in the path of the slidable switch member. 70

3. A ramp shoe for train control systems including a support, a fixed piston carried by the support and normally in communication with an air brake system, a sliding cylinder mounted in the system and cooperating with the piston, said cylinder being mounted for sliding and rotatable movement and having its lower end closed, a ramp engaging member carried by the lower 75 end thereof, a grooved shoulder carried by the cylinder within the support, a movable switch member disposed in operative relation to said shoulder whereby the shoulder is permitted to rotate without imparting movement to the switch, means for guiding the switch member for sliding movement, and fixed switch members in the path of the first switch member. 80

4. A ramp engaging shoe including a casing 90 having an opening in the lower portion thereof, a rotatable and longitudinally slid- able cylinder closed at its lower end slidably journaled in said opening, means for limit- ing the downward movement thereof, a fixed hollow piston carried in the upper end of the casing and slidably fitting the upper end of the cylinder, said casing being adapted to receive air under pressure to fill the cylinder, a ramp engaging shoe detachably connected 100 to the lower end of the cylinder, and cooperative circuit making means carried by and in the path of the cylinder. 105

5. A ramp engaging shoe including a cas- 110 ing having an opening in the lower portion thereof, a rotatable and longitudinally slid- able cylinder closed at its lower end slidably journaled in said opening, means for limit- ing the downward movement thereof, a fixed hollow piston carried in the upper end of the casing and slidably fitting the upper end of the cylinder, said casing being adapted to receive air under pressure to fill the cylin- 115 der, a ramp engaging shoe detachably connected to the lower end of the cylinder, an annular shoulder carried by the cylinder within the casing, a vertical slide frame having spaced lugs to fit astride said shoul- 120 der whereby the same has vertical movement imparted thereto coincident with the move- ment of the cylinder, a switch member car- ried by the same, and fixed switch members in the path of the first mentioned switch member.

6. A ramp engaging mechanism for train 125 control systems comprising a support, a plunger mounted in said support for slid- able and rotatable movement, a ramp en- gaging member carried by the plunger, the 130 said plunger being provided with an air

duct running therethrough, means for connecting said plunger and the air duct therein for communication with the air brake system of the train, an electrical contact member carried by said plunger and a second electrical contact member mounted for slid-
5 able movement only in said support and co-operating with said first contact member during the slidable and rotatable motion of
10 the latter.

7. A ramp engaging mechanism for train control systems including a support, a stationary plunger casing carried thereby and provided with a duct adapted to receive air
15 from an air brake system, a plunger jour-
nalled in said casing and support for slidable and rotatable movement, said plunger carrying a ramp engaging member and being provided with an air duct communicating
20 with the air duct of the plunger casing, and cooperating electrical contacts carried by the plunger and the said support.

8. A ramp engaging mechanism for train control systems including a support, a stationary plunger casing carried thereby and provided with an air duct adapted to receive air from an air brake system, a plunger jour-
25 nalled in said casing and support for slidable and rotatable movement therein, said plunger carrying a ramp engaging member and being provided with an air duct communi-

cating with the air duct of the plunger cas-
ing, an electrical contact member mounted
35 for sliding movement only in said support,
a second electrical contact member carried
by said plunger and slidable with said first
contact member and rotatable relatively
thereto, and additional contact members car-
ried by the support and cooperating with
40 said slidable contact member.

9. A ramp engaging mechanism for train control systems comprising a support, a fixed piston member carried thereby, a cylinder member mounted for slidable movement on said piston member and arranged exter-
45 nally thereon, and cooperating circuit con-
trolling means carried by said support and said cylinder member.

10. A ramp engaging mechanism for train control systems comprising a support, a fixed hollow piston member carried thereby and normally in communication with an air brake system, a hollow cylinder member mounted for slidable movement on said pis-
50 ton member and arranged externally thereon,
the said cylinder member being open at one
end for communication with the air brake
system and being closed at its other end, and
cooperating circuit controlling means car-
ried by the support and the said cylinder. 60

In testimony whereof I affix my signature.

ARCHIBALD G. SHAVER.
